FRAMING SECTION

Reginald Ernest Feakins, Sea Ridge, Frank's Bay,
Southampton, Bermuda

Filed Aug. 16, 1971, Ser. No. 172,356

Term of patent 14 years

Int. Cl. D25—01

U.S. Cl. D13—6

FIG. 1.

FIG. 2.

FIG. 3.

FIG. 1 is a perspective view showing the front, right and top sides of a framing section embodying my new design;

FIG. 2 is a perspective view showing the front, left, and bottom sides of the same framing section as is illustrated in FIG. 1;

FIG. 3 is a cross-sectional view taken along the line 3—3 of FIG. 1;

The cross-sectional configuration is identical from front to back.

The right and left side views are identical.

I claim:

The ornamental design for a framing section, as shown and described.
